RIVET SETTING TOOL

Rudolph M. Babel, Pawtucket, R.I., assignor to United Shoe Machinery Corporation, Flemington, N.J., a corporation of New Jersey

Filed Sept. 19, 1962, Ser. No. 71,781

Term of patent 14 years

(Cl. D54—14)

Fig. 1

Fig. 2

Fig. 3

Fig. 4

FIG. 1 is a right side elevation of a rivet setting tool embodying my novel design;

FIG. 2 is a right side perspective view, as seen looking upwardly from the front of the tool;

FIG. 3 is a front elevation of the tool; and

FIG. 4 is a left side perspective view, as seen looking downwardly from the rear of the tool.

I claim:

The ornamental design for a rivet setting tool, substantially as shown.
